CLAIM

The ornamental design for a glove with loop fastener, as shown and described.

DESCRIPTION

FIG. 1 is a perspective view of a glove with loop fastener, showing my new design;

FIG. 2 is a top plan view thereof;

FIG. 3 is a bottom plan view thereof;

FIG. 4 is a right-side elevational view thereof;

FIG. 5 is a left-side elevational view thereof;

FIG. 6 is a front elevational view thereof; and,

FIG. 7 is a rear elevational view thereof.

The broken lines showing an attachable patch in FIG. 1 depict environmental matter and form no part of the claimed design. The remaining broken lines represent portions of the glove that form no part of the claimed design.
